UNITED STATES PATENT OFFICE.

THADDEUS F. BAILY AND FRANK T. COPE, OF ALLIANCE, OHIO, ASSIGNEES TO THE ELECTRIC FURNACE COMPANY, OF ALLIANCE, OHIO, A CORPORATION OF OHIO.

PHASE-DISTRIBUTION SYSTEM.

1,322,749.

Specification of Letters Patent. Patented Nov. 25, 1919.

Application filed June 27, 1918. Serial No. 242,166.

To all whom it may concern:

Be it known that we, THADDEUS F. BAILY and FRANK T. COPE, citizens of the United States, both residing at Alliance, in the county of Stark and State of Ohio, have invented a new and useful Phase-Distribution System, of which the following is a specification.

This invention relates to phase distribution systems, the object being to employ all three phases of a three phase supply line in the operation of electric furnaces of the resistance type.

With this object in view the invention consists in the novel construction and arrangement of parts, hereinafter described, illustrated in the accompanying drawings, and particularly pointed out in the appended claim, it being understood that various changes in the form, proportions, size and minor details of construction may be made within the scope of the appended claim, without departing from the spirit or sacrificing any of the advantages of the invention.

In the drawings:

Figure 1 is a diagrammatic view illustrating the use of our phase distribution system as applied to an electric furnace of the resistance type in which two oppositely disposed resistance elements are employed.

Fig. 2 is a diagrammatic view illustrating the adaptation of our system to an electric furnace in which a single endless resistance element is employed.

Fig. 3 is a diagrammatic view illustrating the system applied to a furnace employing a single resistance element of the straight trough variety.

Similar numerals of reference indicate corresponding parts throughout the several figures of the drawings.

Various systems have been discovered and are now employed by which electric furnaces of the resistance type designed to employ single phase current can be operated upon a three phase supply line. The means by which the result is accomplished is generally to connect one or two of the phases to the resistor elements within a furnace and the remaining phase or phases to some other piece of apparatus to be operated. In the event that the remaining phase cannot be employed, the two phases which are being employed will naturally unbalance the

line which is obviously an undesirable thing to do.

In order to be able to employ all three phases of a three phase supply line in the operation of an electric furnace, we employ the system herewith shown in which an electric furnace is indicated at 1 and resistance elements at 2 and 3. Electrodes 4, 5 and 6 enter the resistance element 2 and similar electrodes 7, 8 and 9 enter the resistance elements 3. The electrode 6 in the element 2 is exactly twice the distance from the electrode 5 as the electrode 5 is from the electrode 4. This is true also of the electrodes in the resistance element 3, 8 and 9 being exactly twice the distance apart as the electrodes 7 and 8 and since electrodes 4, 6, 7 and 9 are in the extreme ends of their respective elements, electrodes 5 and 8 are positioned exactly one-third of the distance from one end and two-thirds of the distance from the opposite ends of their respective elements. Electrodes 4 and 7 are connected by the wire 10.

A three phase supply line is indicated at 11, all three phases of which connect to the line 12 in which are located primary coils 13, 14 and 15 of three transformers. The secondary coils 16, 17 and 18 co-operate with the coils 13, 14 and 15 respectively. Coils 16 and 17 are connected by a line 19. From this line runs a lead 20 to the electrode 5. Adjustable switches 21, 22 and 23 are designed to operate with the coils 16, 17 and 18 respectively and a line 24 connects the coil 18 and switch 22 and from this line extends a lead 25 which connects to the electrode 8. A line 26 connects the switches 21 and 23 and from this line extend leads 27 and 28 to the electrodes 6 and 9 respectively.

By this arrangement it is seen that all three of the phases are equally used, the resistance elements being connected in series through the medium of the line 10, which joins the electrodes 4 and 7 thus making the resistance elements virtually one continuous element and by the arrangement of the electrodes 5, 6, 8 and 9, the total length of the two resistance elements is divided into thirds.

In the type of furnace employing a continuous circular resistance element such as is shown at 30 in Fig. 2, the electrodes 31, 32 and 33 are each spaced exactly one-third of the length of the element, leads from

these electrodes connect to a line 34 in which is located the secondary coils which are in three phase relation and operate with primary coils from the line 35 to which the 5 three phase supply line 36 is connected.

In Fig. 3 we have illustrated the arrangement of the electrodes in a single straight resistance element, and in this arrangement the electrodes are also spaced at exact thirds 10 of the total length of the element.

From the foregoing it will be obvious that all three phases of a three phase supply line can be used to successfully operate in one furnace a single straight resistance element, 15 two resistance elements, or a plurality, or a continuous resistor without unbalancing the line and without the necessity of connecting another piece of apparatus to maintain the balance upon the line.

20 Having fully described our invention what we claim as new and desire to secure by Letters Patent, is:

In an electric furnace of the resistance type, a pair of resistance elements within said furnace, an electrode located at each 25 end of each resistance element, the electrodes at adjacent ends of one element being connected together, an electrode in each resistance element spaced two-thirds of the distance from one end of the resistance element and one-third of the distance from the other end, a three phase supply line, primary coils of three transformers located in a line connected to the three phase supply line, secondary coils of said transformers 30 located in a second line and connected to the intermediate electrodes of the two resistance elements and to the electrodes spaced the farthest from the intermediate electrodes.

In testimony that we claim the above, we 40 have hereunto subscribed our names.

THADDEUS F. BAILY.
FRANK T. COPE.
